UNITED STATES PATENT OFFICE

2,159,104

EXCAVATING IMPLEMENT TOOTH

Thomas A. Ratkowski, Chicago Heights, Ill., assignor to The American Brake Shoe and Foundry Company, a corporation of Delaware

Application March 1, 1937, Serial No. 128,452

19 Claims. (Cl. 37—142)

This invention relates to that type of excavating implement teeth which, for the sake of prolonging the service of the teeth, has the relatively small portion of its structure which encounters greatest wear and deterioration and usually referred to as "the tip", formed separately from and made replaceable upon the body of the tooth, for instance, as suggested by the cap-like tip of United States Letters Patent No. 2,650,014, issued 5 August 4, 1936, upon the invention of Harry L. Morrison; and particularly that class of such teeth in which the incident of replaceability of the tip is availed of for equipping the implement teeth with divers forms of tips respectively appropriate to different classes of excavated material which the implement may encounter in use. 10 It has been proposed to equip the digging end of an excavating tooth with an axial socket, shaped to receive the shank or tang of a chisel-like penetrating blade, keyed in place by a drift pin and thereby provide the tooth with a readily replaceable penetrating portion of a selected design. An illustration of parts so organized will be found in United States Letters Patent No. 1,816,710, issued July 28, 1931, upon invention of 15 D. H. Young, which produces a tooth which, as a whole, approximates an uninterrupted wedge, comprising a vertically tapered body portion and a correspondingly tapered tip portion assembled through means of a forwardly opening socket in the body portion receiving and fitting a rearwardly presented tang on the tip portion.

One object of the present invention is to combine an axially presented chisel-like tip with a cap-like tip, and replaceably adapt this combination tip to a tooth body as a means of prolonging the usefulness of the tooth and enhancing its capacity for penetration; one adjunctive condition in the preferred construction of this combination type consisting in the inclusion of an attaching tang or shank that enters an axial socket in the tooth so that this shank becomes a means of keying the combination tip to the tooth, and the shank and cap portions together constitute more effective means for rigidly mounting the combination cap on the body of the tooth; and another adjunctive feature of the preferred embodiment consisting in having the shank keyed through means of a drift pin that draws it rearwardly on the body, and having the cap and body wedge-shaped and the chisel tip interengaged with the cap so that the cap is drawn rearwardly to a tapered seating upon the body.

Another object of the present invention is to provide a cap-like tip with a durable metal forward end having any one of several shapes varying from a continuation of the taper of the cap to a desirably elongated penetrating spike so that a plurality of caps, with their separately constructed and variously designed front ends form-

ing combination tips interchangeably applicable to the tooth body, provide means for lending various shapes to the digging tooth appropriate to different services which it must render, aside from providing in each instance a means of reducing 5 deterioration of the tooth.

The invention contemplates a cap-like tip having a tapered seating upon a socketed wedge-shaped body or tooth nose, with a forwardly opening passage in the end of the cap registering with the socket of the nose through which the attaching shank of the chisel end may pass in entering said socket; the chisel-tip being interengaged with the cap tip in a manner to permit the cap tip to be drawn to its seat by the 10 shank of the chisel tip, for instance, by welding one tip member to the other or by shouldering the chisel tip upon the cap tip, with or without a bearing of substantial axial extent of the tip within the cap.

Other objects, features, capabilities and advantages are comprehended by the invention, as will later appear and as are inherently possessed thereby.

The present application forms a continuation-in-part of my application Serial No. 98,269, filed 25 August 28, 1936, for Excavating implement teeth, which application has been abandoned.

Referring to the drawings:

Figure 1 is an axial section in a horizontal plane of one embodiment of the present invention;

Figure 2 is a side elevation, partly in section, in an axial plane at right angles to that of Figure 1;

Figure 3 is a horizontal axial section of a modified construction;

Figure 4 is a side elevation, partly in axial section, of a tooth embodying the construction of Figure 3;

Figure 5 is a plan view, partly in section, of a further modified construction; and

Figure 6 is a side elevation, partly in axial section, of a tooth embodying the construction of Figure 5.

1 represents a tooth body which may be constructed in a known manner, with divergent jaws 2 and bifurcated shank 3 by which it may be fitted to a tooth base which is in turn mounted upon an excavating implement, which said body likewise includes a forwardly presented wedge-shaped nose 4 in which is formed the axial socket 5 for the anchoring tang or shank 6 of a chisel point 7 (Figures 1 and 2) or shank 6a of a chisel point 7a (Figures 3 and 4) or shank 6c of a chisel point 7c (Figures 5 and 6); also a transverse bore 8 in offset registry with the opening 9 in said shank and adapted to receive a known type of drift pin for keying the shank to the body.

According to the present invention, the chisel 60

tip 7 is not applied directly to the tapered nose 4 of the body 1 but indirectly through the medium of a cap member 10 of box-like form which has taper-seating upon the nose 4 and is constructed with opening 11 in its forward end so that the chisel tip can be mounted upon and interengaged with the cap tip in a manner to receive stabilizing support from the cap and at the same time enable it to force the cap to its tapered seating by rearward tension imposed upon the shank 6 by the pin that enters the bore 8. The confines of the forward opening 11 in the cap 10, according to Figures 1 and 2, are thickened in the direction of the axis of the tooth so as to enlarge the surfaces through which they receive the shank 6 to provide wall sections axially beyond the body portion which are enlarged in the direction of the axis of the tooth; said shank is flared forwardly and laterally at its union with the tip 7 in the interest of ruggedness of construction and to enable the confines of the opening 11 to provide extended shoulders through which thrust of the tip 7 may be transmitted when the tooth is in service, or through which the rearward seating pressure may be transmitted from the shank 6 as aforesaid.

According to Figures 3 and 4, the forward opening 11a has its confines provided by the thickness of the cap walls although the flaring shoulders 6b at the base of the shank still prevail as a source of lateral rigidity of the shank relatively to the tip 7, and the mounting of the tip 7 upon the cap 10a, as well as interengagement between these two members of the combination tip, is insured through means of welding 12 applied in any approved manner.

While the design of the chisel member 7 of the combination tip, as illustrated in Figures 1 and 2, provides the penetrating portion 7b and the base 7c, the latter in substantial continuation of the taper of the nose and its closely fitting cap 10, it is to be understood that the portion 7a of this tip member may be of any desired length appropriate to the work to be performed by the tooth, and the wedge-shaped portion 7c may continue to a forward edge and serve merely as a continuation of the digging wedge defined by the outer surfaces of the cap 10, thus providing an improved construction of the cap form of tip. Or, as shown in Figure 4, the blade which constitutes the integral shank 6a and chisel tip 7d is of uniform thickness throughout and welded into the forward end of the cap opening. The exposed portion 7d, however, may be of any desired length or form.

According to Figures 5 and 6, the tooth body 1 is provided with a wedge-shaped nose 4a having the upper and lower surfaces stepped as at 13 and 14, respectively, to receive the cap member 15 of box-like construction. The cap member 15 is provided with the opening 16, this opening being defined at the top and bottom thereof by the inclined surfaces 17 and 18 adapted to have seating relation with the inclined surfaces 19 and 20, respectively, on the rear portion of the chisel blade head. This opening 16 is further defined on the sides by the inclined surfaces 21 and 22 which merge with the seating surfaces 23 and 24, respectively, at the forward end of the cap, which surfaces are adapted to cooperate in seating relation with rearwardly exposed surfaces extending between surfaces 17 and 18 on the rear portion of the chisel blade head.

It will be noted that the wall portions of the cap member forming the confines of the opening 16 are thickened or enlarged transversely and

axially in respect to the tooth to provide suitable bearing surfaces between the cap member and the chisel point or tip and to provide a rugged and strong construction. Shank 6c is flared forwardly and laterally at its union with the tip 5 1c, the flared portions being provided with the surfaces 25 and 26 which cooperate with the cap member so as to prevent transverse relative movement between these two elements of the construction and to thereby steady the blade 10 portion of the tip relatively to the body.

In this embodiment the blade portion is formed separately from but integrally united to the cap member by a welding fillet 25 extending around the unit comprising the blade portion and cap 15 member, said fillet being disposed within a V or triangular shaped recess formed in part by the surfaces 26 at the rear portion of the chisel blade, the upper and lower surfaces 26 forming a portion or extension of the inclined surfaces 17 and 18, and in part by inclined surfaces 27 formed on the exposed face of the forward end of the cap member 15. This welding fillet insures proper interengagement between the blade portion and cap member to maintain these elements 25 as a unit rigid in construction and adapted to withstand the wear incident to hard usage thereof. It is to be noted that welding fillet 25 forms a substantial continuation between the surfaces of the blade portion and the cap member. 30

Although the chisel point or tip is shown with the upper and lower surfaces of substantially uniform taper from the rear to the front, it is of course understood and appreciated that this chisel point or tip may be constructed as disclosed in Figures 1 to 4 inclusive. 35

An important feature contemplated in the preferred embodiment of the present invention is the merger of the outer faces of the cap portion of the combination tip into or their continuation 40 in faces of the blade portion of said combination tip in a manner to avoid offset or shoulder at the plane of merger, with consequent protection of the forward end of the cap portion and improvement in digging effect by causing the merged 45 faces to function as continuing faces corresponding, respectively, to the combined longitudinal dimensions of the blade and cap portions.

In Figures 3 to 6 inclusive the welding provides a fillet which in a measure constitutes a 50 substantial degree of merger or uninterrupted continuance between the surfaces of the cap and blade.

If desired, the cap portion of the compound tip structure can be provided with openings in 55 position to receive a key pin passing transversely through the body of the tooth as taught in United States Letters Patent No. 2,050,014, aforesaid, and this keying may be in addition to or substituted for the keying which involves the inner end 60 of the shank.

While I have herein described and upon the drawings shown an illustrative embodiment of the invention, it is to be understood that the invention is not limited thereto but may comprehend other constructions, arrangement of parts, details and features without departing from the spirit of the invention. 65

I claim:

1. A tooth for an excavating implement, comprising a body member having a forwardly presented nose constructed with a forwardly opening longitudinal bore, a combination tip structure comprising a cap portion and a blade portion, said cap portion embracing the end and sides of 70

- and protecting the nose against wear and preventing relative lateral displacement between the cap and the nose, said cap having forwardly presented bearing surfaces, and said blade portion 5 having bearing surfaces cooperating with said first-named bearing surfaces and provided with a shank extending through said cap and into the socket of the nose, and means for keying said tip structure in position.
- 10 2. A tooth for excavating implements as described in claim 1, in which the blade portion has lateral bearing in the cap portion that prevents transverse relative movement between them, and thereby steadies the blade portion of the tip 15 relatively to the body.
3. An excavating implement tooth as described in claim 1, in which the blade portion is formed with rearwardly presented shoulders through which it bears rearwardly against the cap portion, and the cap portion is provided with wall sections which are enlarged in the direction of the axis of the tooth to develop bearings for said shoulders and to assist in sustaining the blade portion against transverse relative movement 25 upon the cap portion.
4. A tooth for excavating implements as described in claim 1, in which the cap portion in its embracing relation with the nose extends axially beyond the end thereof to provide a seat for 30 said blade portion.
5. A tooth for excavating implements as described in claim 1, in which the cap portion in its embracing relation with the nose extends axially beyond the end thereof to provide a seat 35 for said blade portion, and in which the cap portion is provided with wall sections disposed beyond the end of said nose and which are enlarged in the direction of the axis of the tooth.
6. A tooth for excavating implements as described in claim 1, in which the cap portion in its embracing relation with the nose extends axially beyond the end thereof to provide a seat for 40 said blade portion, and in which the bearing surfaces of said cap portion are curved for cooperative relation with said blade portion.
7. A tooth for excavating implements as described in claim 1, in which the cap portion in its embracing relation with the nose extends axially beyond the end thereof to provide a seat for 45 said blade portion, and in which the bearing surfaces of said cap portion are curved laterally for cooperative relation with said blade portion.
8. A tooth for excavating implements as described in claim 1, in which the cap portion in its embracing relation with the nose extends axially beyond the end thereof to provide a seat for 50 said blade portion and is provided with wall sections enlarged in the direction of the axis of the tooth, and in which the bearing surfaces of said cap portion are curved for cooperative relation with said blade portion.
9. A tooth for excavating implements as described in claim 1, in which the cap portion in its embracing relation with the nose extends axially beyond the end thereof to provide a seat for 55 said blade portion and is provided with wall sections enlarged in the direction of the axis of the tooth, and in which the bearing surfaces of said cap portion are curved laterally for cooperative relation with said blade portion.
- 70 10. A tooth for excavating implements as described in claim 1, in which the cap portion in its embracing relation with the nose extends axially beyond the end thereof to provide a seat 60 for said blade portion, and the blade portion is formed separately from but integrally united to the cap portion.
11. A tooth for excavating implements as described in claim 1, in which the blade portion 5 is formed separately from but integrally united to the cap portion and the cooperating bearing surfaces of said blade and cap portions are tapered.
12. A tooth for excavating implements as described in claim 1, in which the cap portion is formed separately from but integrally united to the blade portion and in which the cooperating bearing surfaces of said cap and blade portions are tapered and the cap portion has tapered seating surfaces cooperating with similar surfaces on 15 said body member.
13. A tooth for excavating implements as described in claim 1, in which the cap portion is formed separately from but integrally united to the blade portion and in its embracing relation 20 with the nose extends axially beyond the end thereof to provide a seat for said blade, and in which the cooperating bearing surfaces on said cap and blade portions are tapered.
14. A tooth for excavating implements as described in claim 1, in which the blade portion is formed separately from but integrally united to the cap portion and has lateral bearing in the cap portion that prevents transverse relative 25 movement between the same.
15. A tooth for excavating implements as described in claim 1, in which the blade portion is formed separately from but integrally united to the cap portion, and wherein the cooperating bearing surfaces of said blade and cap portion 30 are tapered and said blade portion has lateral bearing in the cap portion that prevents transverse relative movement between the same.
16. A tooth for excavating implements as described in claim 1, in which the cap portion in its embracing relation with the nose extends axially beyond the end thereof to provide a seat for 35 said blade portion, and in which the bearing surfaces of said cap portion are tapered for cooperative relation with said blade portion.
17. A tooth for excavating implements as described in claim 1, in which the cap portion in its embracing relation with the nose extends axially beyond the end thereof to provide a seat for 40 said blade portion, and in which the bearing surfaces of said cap portion are tapered in an axial direction for cooperative relation with said blade portion.
18. A tooth for excavating implements as described in claim 1, in which the cap portion in its embracing relation with the nose extends axially beyond the end thereof to provide a seat for 45 said blade portion and is provided with wall sections enlarged in the direction of the axis of the tooth, and in which the bearing surfaces of said cap portion are tapered for cooperative relation with said blade portion.
19. A tooth for excavating implements as described in claim 1, in which the cap portion in its embracing relation with the nose extends axially beyond the end thereof to provide a seat for 50 said blade portion and is provided with wall sections enlarged in the direction of the axis of the tooth, and in which the bearing surfaces of said cap portion are tapered in an axial direction for cooperative relation with said blade portion.
